DESIGN FOR A HANDKERCHIEF

Julius Marcus, New York, N. Y.

Application January 2, 1937, Serial No. 66,855

Term of patent 3½ years

To all whom it may concern:

Be it known that I, Julius Marcus, a citizen of the United States of America, residing in city of New York, county of New York, and State of New York, have invented a new, original, and ornamental Design for a Handkerchief, of which the following is a specification, reference being had to the accompanying drawing, forming part thereof.

The figure of the drawing is a quarter section of a handkerchief showing my new design, the other three sections being identical with that here disclosed, arranged in proper relation to complete the handkerchief.

I claim:

The ornamental design for a handkerchief substantially as shown and described.

JULIUS MARCUS.
